A. SCHNEELOCH.
LINE SPACING MECHANISM FOR TYPE WRITERS.
APPLICATION FILED MAR. 17, 1913.

Patented Dec. 7, 1915.

Fig. 1.

UNITED STATES PATENT OFFICE.

AUGUST SCHNEELOCH, OF ONEIDA, NEW YORK, ASSIGNOR, BY DIRECT AND MESNE ASSIGNMENTS, OF ONE-HALF TO THE OLIVER TYPEWRITER COMPANY, OF CHICAGO, ILLINOIS, A CORPORATION OF ILLINOIS, AND ONE-HALF TO UNDERWOOD TYPEWRITER COMPANY, OF NEW YORK, N. Y., A CORPORATION OF DELAWARE.

LINE-SPACING MECHANISM FOR TYPE-WRITERS.

1,163,563.

Specification of Letters Patent.

Patented Dec. 7, 1915.

Original application filed April 7, 1900, Serial No. 11,993. Renewed August 9, 1910, Serial No. 576,392. Divided and this application filed March 17, 1913. Serial No. 754,908.

To all whom it may concern:

Be it known that I, AUGUST SCHNEELOCH, a citizen of the United States, residing at Oneida, county of Madison, and State of New York, have invented new and useful Improvements in Line-Spacing Mechanisms for Type-Writers, of which the following is a specification.

My invention relates to a line spacing mechanism for typewriting machines and consists in a new arrangement and construction of parts adapted to operate in an improved manner for the accurate spacing of lines of typewriting.

My improved device is desirably constructed in the manner to be described whereby it may conveniently be set to space one, two, three or more lines, or entirely to throw the line spacing device out of operation.

This application is a division of my renewal application Ser. No. 576,392 filed August 9, 1910, originally filed April 7, 1900, Ser. No. 11,993, Patent 1,058,907, April 15, 1913.

My invention is fully shown in the drawing herewith, in which the reference numerals of the description indicate the corresponding parts in the figures.

Figure 1 illustrates an embodiment of my invention in side elevation. Fig. 2 is a plan view thereof and Fig. 3 shows in elevation the spacing cam detached.

In the figures, 138 indicates a shaft to which the platen 139 is attached to be carried by the usual carriage not shown; and attached to the same shaft is the ratchet wheel 140. Loosely mounted on said shaft, in proximity to said ratchet wheel 140, is a cam disk 141, against which impinges, so as to hold it in position, spring catch 142, and said disk 141 is provided with a knob 143, to move it as the operator may desire against the action of said spring 142. Said disk 141 is provided with cams and notches as shown in the drawings in connection with which the sliding pawl 144 may operate. As best shown in Fig. 3 the cam disk has a solid upper portion to engage with the pawl 144 and hold it out of engagement with the

teeth, and a cut-away portion to permit engagement with the teeth. Said pawl 144 is borne by swinging arm 145 journaled upon sliding bar 146, as shown in Figs. 1 and 2, and is held so as to operate both with said cam disk 141 and said ratchet wheel 140 by means of spring 147. The forward stroke of said pawl is limited by the end 148 of said swinging arm 145 striking against abutment 149, screwed on the side of the platen frame as shown in Figs. 1 and 2. It is apparent that if said cam disk were not provided, upon each forward movement of the pawl, as the bar 146 was moved forward, it would carry the ratchet wheel 140 and with it the platen, the full limit of its stroke, in this case making the space of three lines. When, however, the cam disk is applied, by turning the same by means of its knob 148, it will readily be understood that the pawl 70 may be held from engagement with the ratchet wheel for the space of either one or two or all of the ratchets, so that a space of one or two lines may be made, or the pawl, and thereby the spacing mechanism, may be 75 thrown out of operation entirely and the platen be allowed to rotate freely at the will of the operator, by means of the hand-knob 150, at each end of the same. The parts are here shown in position to permit 80 of operation in the last mentioned manner and it will be seen that a high portion 156 of the cam 141 is in engagement with the roller 152 to hold the roller away from engagement with the ratchet 141. The catch 85 142 is then in engagement with a notch 154 of the cam. Upon rotating the cam to the left so that the catch 142 engages a notch 155 the high portion 156 of the cam engaged by the pawl 144 will permit the engagement 90 of the pawl with the ratchet at a position whereby its further movement will advance the platen a distance of one tooth. When so moved the high portion 156 of the cam is moved from engagement with the roller 152 95 so that the roller is permitted to act upon the ratchet teeth. Upon further moving the cam to effect engagement of the catch with notch 157 the position of engagement of the pawl 144 with the ratchet permits of 100

its rotating the ratchet a distance of two teeth thereof and a similar adjustment to effect engagement of the catch with notch 158 permits a movement of the platen a distance of three teeth.

Spring arm 151, with its roller 152 is the ordinary device to control the movement of the ratchet wheel 140, which it will be understood is thrown out of operation by 10 cam disk 141, when said platen is allowed to move freely at the will of the operator.

Having described my invention, I claim,—

1. A line spacing device for typewriting machines comprising a ratchet wheel connected with the shaft of the platen, a movable cam element arranged adjacent thereto, a reciprocative slide, a pawl arm pivotally attached to the slide, a pawl on the arm to engage the ratchets of the wheel to turn 15 the platen, said cam element having an elevated and a cut-away portion respectively to withhold and permit the engagement of the pawl with the ratchets and having notches to correspond to its positions of adjustment 20 and a yieldable retaining element to engage said notches whereby the cam element is retained in its adjusted positions.

2. A line spacing device for typewriting machines comprising a ratchet wheel connected with the shaft of the platen, a movable cam element arranged adjacent thereto, a reciprocative slide, a pawl arm pivotally attached to the slide, a pawl on the arm to engage the ratchets of the wheel to turn 25 the platen, said cam element having an elevated and a cut away portion respectively to withhold and to permit the engagement of the pawl with the ratchets, a stop arranged in the path of the arm to be engaged thereby to limit the feed movement of the slide 30 and pawl and means for retaining the parts in relative positions to permit the pawl to

advance the ratchet a distance of one or more teeth.

3. A line spacing device for typewriting 45 machines comprising a ratchet wheel connected with the platen, a cam element arranged adjacent thereto, an operating pawl adapted to work in the ratchets of said wheel so as to turn the same, the cams on the cam element being so arranged that upon the operative movement of said pawl the same may be held from engagement with the ratchet throughout a desired distance of its movement, means for retaining the 50 cam element in adjusted position, a yieldable platen retaining element arranged to engage the ratchets and adapted to be thrown out of operation in one position of the cam element.

4. A line spacing device for typewriting 55 machines comprising a ratchet wheel connected with the platen, a cam element arranged adjacent thereto, an operating pawl adapted to work in the ratchets of said 60 wheel so as to turn the same, the cams on the cam element being so arranged that upon the operative movement of said pawl the same may be held from engagement with the ratchet throughout a desired distance of its movement, means for retaining the cam element in adjusted position, a resilient 65 roller support suitably arranged, a roller carried by said support to engage the ratchets whereby the platen is retained and said 70 cam element being arranged to throw said roller out of operation in one position.

In testimony whereof I have signed my name to this specification in the presence of two subscribing witnesses.

AUGUST SCHNEELOCH.
